(57) **CLAIM**

We claim the ornamental design for a part of a vacuum cleaner, as shown and described.

DESCRIPTION

FIG. 1 is a perspective view of a part of a vacuum cleaner showing our new design;

FIG. 2 is a front view thereof;

FIG. 3 is a rear view thereof;

FIG. 4 is a plan view thereof from above;

FIG. 5 is a plan view thereof from below;

FIG. 6 is a side view thereof; and,

FIG. 7 is a side view of the opposite side of FIG. 6.

1 Claim, 2 Drawing Sheets

FIG. 4**FIG. 5****FIG. 6****FIG. 7**
